UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,175,009.

Specification of Letters Patent. Patented Mar. 14, 1916.

Application filed October 23, 1914. Serial No. 868,810.

To all whom it may concern:

Be it known that I, JOHN F. O'CONNOR, a citizen of the United States, residing at Chicago, in the county of Cook and State of Illinois, have invented a certain new and useful Improvement in Draft-Riggings for Railway-Cars, of which the following is a full, clear, concise, and exact description, reference being had to the accompanying drawings, forming a part of this specification.

This invention relates to improvements in draft riggings for railway cars.

An object of the invention is to provide a spring draft rigging for railway cars consisting of few parts of relatively inexpensive construction and which may be readily assembled and disassembled.

In the drawing forming a part of this specification, Figure 1 is a longitudinal vertical sectional view of a draft rigging, showing one embodiment of my improvements. Fig. 2 is a horizontal sectional view taken substantially on the line 2—2 of Fig. 1 and Fig. 3 is a vertical sectional view taken substantially on the line 3—3 of Fig. 1.

In said drawing, 10—10 denote the center sills or other draft members, the same being provided with rear slots 11—11 and elongated front slots 12—12. Mounted within the rear slots 11—11 is a stationary key 13, the latter having mounted thereon and between the sills, a hollow casing 14 which, as shown, is substantially rectangular in cross section and provided with an integral front wall 15, said wall 15 being slotted as indicated at 16 on the sides thereof to receive therethrough the forwardly extended side arms 17 of a yoke 18, the rear end 19 of the yoke forming a rear follower in engagement with the key 13. The side arms 17 of the yoke are provided with elongated slots 20 at the front thereof to receive the coupler key 21 by which said yoke is connected to the draw bar 22. Mounted within the casing 14 and between the front wall 15 thereof and the rear portion 19 of the yoke, are nested springs 23. The inner faces of

the side walls 24 of the casing 14 are recessed 50 or grooved, as indicated at 25, to form guideways for the side arms 17 of the yoke. And said side walls are furthermore provided with elongated slots 26 to thereby permit the casing 14 to slide back and forth 55 on the key 11.

The operation of the device is as follows:—Upon inward movement of the draw bar, the front wall 15 of the casing 14 is engaged by the rear end of the draw bar 60 and the springs compressed between it and the rear portion 19 of the yoke which acts as a follower, the same being held from rearward movement by the key 13. The rearward movement of the casing 14 is provided for by the elongated slots 26. Under draft, the yoke 18 is pulled forwardly by means of the key 21 and the springs 23 compressed between the rear wall thereof and the front end or wall 15 of the casing 14. 70

Although I have herein shown and described what I now consider the preferred embodiment of my improvement, yet I am aware that various changes and modifications may be made in the details and arrangement of parts, without departing from the spirit of the invention, and I contemplate all such changes and modifications as come within the scope of the claims appended hereto.

I claim:—

1. In a draft rigging of the character described, the combination with draft sills, of a stationary key mounted in said sills, a casing slidably mounted on said key and provided with a front end wall and open at the rear, a yoke mounted within said casing and having arms extended forwardly through openings in the front wall of said casing and adapted to be connected to a draw bar, said yoke being insertible longitudinally within the casing through the open rear end of the latter, and cushioning means interposed between said front wall and the rear end of said yoke.

2. In a railway draft rigging, the combination with draft sills, of a slidably mounted casing mounted between said sills and

2
having a closed end wall and open at its other end, a yoke slidably mounted within said casing and having its ends extended through openings in said closed end wall, 5 cushioning means interposed between said end wall and said yoke, said casing being provided with guideways formed on the inner walls thereof for the arms of said yoke.

JOHN F. O'CONNOR.
